UNITED STATES PATENT OFFICE.

WILLET C. WELLS AND FRANK E. WELLS, OF COLUMBUS, OHIO.

PROCESS OF EXPRESSING WAX FROM PETROLEUM DISTILLATES.

1,350,482.

Specification of Letters Patent. Patented Aug. 24, 1920.

Application filed April 23, 1914. Serial No. 833,897.

To all whom it may concern:

Be it known that we, WILLET C. WELLS and FRANK E. WELLS, citizens of the United States, residing at Columbus, in the county 5 of Franklin and State of Ohio, have invented certain new and useful Improvements in Processes of Expressing Wax from Petroleum Distillates, of which the following is a specification.

10 The lubricating oil portion of the distillates of most petroleums contain elements that congeal at normal temperatures into a blending of crystalline wax and petroleum jelly, or vaseline, which is very difficult to 15 separate by presses in use from the portion that is desired for low cold test lubricating oil; consequently the practice has always been to decompose such distillates by redistillation, termed cracking, thereby depriving 20 them of a great portion of their value, and reducing them to about 60 viscosity to make them expressible. The process of expressing the wax-bearing portion of the petroleum distillate has hitherto been carried on 25 with an apparatus consisting of the arrangement in series of vertical plates usually provided with a central bore and having corrugated or perforated faces covered with heavy, closely woven cotton fabric; between 30 said plates are interposed spacing rings, and when the desired number of such plates and spacing rings is arranged, they are mechanically clamped or secured together. The chilled semi-fluid wax distillate is then 35 introduced under pressure through the central bore mentioned above, and the liquid portion is forced through the fabric, and the wax portion remains in the ring spaces. However, the thread of cotton fabric is al- 40 most impervious to the oil under pressure, and a further difficulty is presented by the great area of solid metal backing of the fabric through which of course the oil can- 45 not pass, and these conditions collectively so impede the passage of oil through the fabric that a reasonably viscid wax bearing distillate very soon fills and coats the fabric to complete obstruction.

We have found that we can produce 50 greatly improved results by using a mat or plate built up of heavy, closely woven wire with fine, closely woven wire covering there- 55 for, and over all a closely woven woolen fab- ric is placed. We have found that the oil filters readily through both the interstices and the threads of the woolen fabric, that

there is no cause for rupture of the fabric, and that the fineness of the wire mesh em- 60 ployed offers practically no resistance to the passage of the oil through the fabric. The mats or plates thus built up are arranged vertically in a series with spacing rings in- 65 terposed therebetween and mechanically se- cured together, a central bore being provided through said series of mats. Further rein- 70 force- ment by means of a skeleton structure is provided for the mat and the minimum of obstruction is offered to the drainage, while the required rigidity and stability are im- 75 parted to the structure.

We introduce the distillate under pressure 80 through the central bore and the oil readily passing through the mats flows into an ap- 85 propriate collector.

Consequently by moderate pressure we can 90 separate from uncracked or viscid wax bearing distillates retaining their full inherent body and structure the part thereof that con- 95 geals into wax or vaseline, and produce oil that is perfect for lubricating purposes, of 100 viscosity over 300, and which may be used without congealation at very low tempera- 105 tures.

Our invention therefore is the process of expressing from uncracked distillates of 110 petroleum the portion thereof that congeals 115 into wax or vaseline, by physical separation entirely carried on through a uniformly pervious strainer supported uniformly by structure that offers the minimum of resist- 120 ance to the passage of the strained product.

The apparatus used in our process, and the construction of the mat or plate mentioned, appear in the accompanying drawings which are hereby made a part of this specifica- 125 tion, in which Figure 1 shows the filter press and the arrangement of filter mats and ring spacers between; Fig. 2 shows the filter mat with parts broken away in order to dis- 130 close the construction thereof; Fig. 3 shows the ring spacer; Fig. 4 shows a section of the mat and contiguous ring spacers on a greatly enlarged scale for the purpose of illustration; and Fig. 5 shows an end view of the 135 apparatus partly broken away.

In the accompanying drawings, the frame supports are shown at 1 and 1^a, frame sup- 140 port 1 carrying the platen 8 which may preferably be integral with the frame. Frame rods 2 and 3 are mounted at one end 145 in platen 8, and at the other in the frame support 1^a. Tie rods as at 4, 5, 6, 7, in such

number as desired are secured at one end in the platen 8, and at their opposite ends are arranged to enter the platen 9, which is movably mounted on the frame rods 2 and 3.

The filter mat 10 is composed of the layers of wire of different fineness of mesh shown at 11, 12, 13, covered on both faces with the woolen fabric 14 and 15, the whole being 10 appropriately secured together. A central opening 16 pierces the filter mat 10 for the admission of the distillate or compressed air as desired, for the purpose of drying the charge.

15 Between each two mats when set up in their vertical position for use is interposed a ring 17 whereby the mats are spaced apart, providing a compartment into which the distillate is forced for filtration, and in 20 which the wax residue is deposited. The ring 17 carries diametrically disposed rods 17^a, 17^b, which provide rigid lateral support for the body of the filter mat and prevent any tendency thereof to warp or sag under 25 the pressure of the distillate or the air used in the process. Each ring is provided with hangers 18 and 19 on opposite sides thereof which rest upon the frame rods above described when the ring is in position. Similar hangers 20 and 21 are provided on each 30 mat.

It will be noted that the entire face of the said mat or disk is pervious and therefore utilizable for filtration purposes, and consequently offers the minimum of obstruction to the passage of oil.

A hydraulic cylinder 22 is mounted on the frame support 1^a for forcing the end plate 9 upon the filter when the mats and rings are in position for use. In building up the filter for use a mat is placed against the end plate 8, a ring is then placed against the mat, a second mat is placed against the said ring, a second ring is then 45 placed against said second mat, and so on alternately until the desired number of mats and rings are arranged to constitute the filter press. The end plate 9 is thereupon brought up against the last mat and power 50 is applied through the hydraulic cylinder by the ram 23 until the pressure reaches the degree desired, whereupon the nuts are turned upon the free ends of the rods 4, 5, 6, 7, and the end plate 9 is thereby fixed in 55 position. The press is now ready for use and the petroleum distillate in any appropriate way may be introduced into the central bore 24 under sufficient pressure to force

it into all the ring spaces and through the filter mat, whence the oil percolates through 60 the mesh of the mat and is caught in the drain or receiver 25. The pressure at which the distillate is being introduced into the press may be increased as the quantity of wax in the ring spaces increases, until the 65 desired dryness of the wax is accomplished. Ordinarily we cease the introduction of the distillate before we complete the run, and effect a uniform degree of dryness of the wax with which the ring spaces are 70 charged by the use of compressed air, which may be appropriately introduced into the press through the opening 24, and thereby the pressure upon the wax is continued without the introduction of additional distillates, until the wax residue becomes comparatively solid and ready for removal from the press. Thereupon the press is knocked down, the wax is removed, and the press is again built up for further service. 75

What we claim is:

1. The herein described process of obtaining low cold test oils from viscid distillates of petroleum and the like consisting in feeding the distillates to a woolen fabric strainer 80 which is uniformly and adequately supported by structure that does not materially obstruct the strainer, under sufficient pressure to express the oils from the distillate.

2. The herein described process of obtaining low cold test oils from viscid distillates of petroleum and the like, consisting in feeding the distillates to a woolen fabric strainer which is uniformly and adequately supported by structure that does not materially obstruct the strainer, under sufficient pressure 95 to express the oils from the distillate, and increasing the pressure as the wax accumulates on the face of the strainer.

3. The herein described process of obtaining low cold test oils from viscid distillates of petroleum and the like, consisting in feeding the distillates to a series of spaced apart woolen fabric strainers uniformly and adequately supported by structure that does 100 not materially obstruct the strainer and furnishes unrestricted drainage there-through, under sufficient pressure to express the oils from the distillate.

In testimony whereof we affix our signatures in the presence of two witnesses.

WILLET C. WELLS.
